PUMP WITH SEALED IMPELLER HUB

Warren Doble, North Hollywood, Calif., assignor to Jabsco Pump Company, Burbank, Calif., a corporation of California

Application August 22, 1955, Serial No. 529,713

13 Claims. (Cl. 103—117)

The present invention relates in general to rotary pumps and, since it is particularly applicable to rotary pumps having impellers of rubber, or like materials, it will be considered in such connection herein for purposes of illustration.

This specification discloses subject matter which is disclosed and claimed in the copending application of Robert E. Yaugher and myself, Serial No. 447,163, filed August 2, 1954, now abandoned, reference to which is hereby made.

The aforementioned copending application discloses a rubber-impelled pump which includes a pump housing having an impeller chamber, a shaft having a projecting end extending inwardly into the impeller chamber, a cup-shaped hub telescoped over and enclosing the projecting end of the shaft, an impeller bonded onto the hub and disposed in the impeller chamber, an inwardly struck dimple on the hub disposed in a recess in the shaft to transmit rotation of the shaft to the hub, and sealing means engaging the pump housing and the hub outwardly of the impeller chamber for providing a fluid-tight seal between the pump housing and the hub, the hub projecting outwardly beyond one end of the impeller for this purpose.

The foregoing construction provides a very simple means of mounting the impeller on the shaft and provides a relatively loose torque-transmitting connection between the impeller hub and the shaft so that the impeller and its hub can be removed readily for cleaning, replacement, or the like. Since the hub encloses the end of the shaft which projects into the impeller chamber and since the sealing means mentioned engages the pump housing and the hub intermediate the ends of the hub, the pumped fluid, which may be corrosive, cannot come into engagement with the shaft to corrode the shaft and possibly cause the impeller hub to stick thereto so that it is difficult or impossible to remove, particularly where the shaft is a steel shaft susceptible to rusting.

Because of the foregoing, the impeller and hub are readily replaceable in a minimum of time and with simple tools, this being an important feature, particularly in marine installations where satisfactory pump operation may be a life or death matter.

Even with the foregoing advantages of the construction illustrated in the copending application mentioned, I have found that some corrosion of the shaft may take place within the hub, particularly in the corrosive atmospheric environment found in marine applications of the invention. Such shaft and/or hub corrosion occasionally makes the impeller difficult to remove from the shaft, particularly in the case of a steel shaft, which is undesirable for the reasons mentioned.

Considering how this corrosion of the shaft within the impeller hub may occur, despite the fact that the pumped fluid is prevented from coming in contact with the shaft by the aforementioned sealing means between the hub and the pump housing, the impeller hub and the shaft

2

rotate on slightly different axes because of the side load imposed on the impeller by the discharge pressure of the pumped fluid and the flexing of the vanes as they engage the vane-flexing cam. Such rotation of the hub and the shaft about slightly spaced axes cannot be prevented without sacrificing the relatively loose mounting of the hub on the shaft, which would be undesirable since it would make the impeller extremely difficult to remove and would make it impossible to remove without special tools and equipment. Since the hub and the shaft do rotate about slightly different axes, there is always a crescent-shaped space or clearance between the shaft and the hub, and the configuration of this space changes during each revolution because some slippage between the hub and the shaft occurs. This changing configuration of the crescent-shaped space between the hub and shaft results in a pumping action so that air is pumped into and out of such space as the shaft and impeller hub are rotated. Consequently, if the pump is operated in a corrosive atmosphere, such as the damp and salty atmosphere characteristically associated with the ocean, the air pumped or circulated through the clearance between the impeller hub and the shaft tends to corrode both of these elements, and particularly tends to rust the shaft if it is formed of steel. Such corrosion may result in extreme difficulty in removing the impeller and its hub from the shaft for replacement purposes, which is obviously undesirable since it may place human life in jeopardy.

In view of all of the foregoing, a primary object of the invention is to provide a pump having sealing means for providing a fluid-tight seal between the hub of the impeller and the shaft so that no circulation of the atmosphere in which the pump is operated can take place through the clearance between the impeller hub and the shaft. This factor, coupled with isolating the shaft from the pumped fluid in the manner hereinbefore outlined, results in a structure wherein the shaft is substantially completely freed of corrosive influences. Consequently, the impeller and its hub may always be removed readily with substantially no possibility of sticking to the shaft, which is an important feature of the invention.

Another object is to provide a sealing means between the hub and the shaft which includes a sleeve encircling the shaft and engaging the outer end of the hub, beyond the sealing means between the hub and the pump housing. A related object is to provide the hub with a convergent outer end engaged by the sealing sleeve to insure a fluid-tight seal.

Still another object is to provide resilient means encircling the sealing sleeve mentioned for biasing the sealing sleeve into fluid-tight engagement with both the convergent outer end of the hub and the shaft.

Another object is to provide a bearing for the shaft which is also engaged by the sealing sleeve, whereby the sealing sleeve performs the dual function of excluding air from the clearance between the hub and the shaft and from the bearing.

The foregoing objects, advantages, features and results of the present invention, together with various other objects, advantages, features and results thereof which will be evident to those skilled in the art in the light of this specification, may be attained with the exemplary embodiments of the invention which are illustrated in the accompanying drawing and which are described in detail hereinafter. Referring to the drawing:

Fig. 1 is a longitudinal sectional view of one embodiment of a pump of the invention;

Fig. 2 is an enlarged, fragmentary, sectional view duplicating a portion of Fig. 1; and

Fig. 3 is a fragmentary, sectional view similar to a

portion of Fig. 1 but illustrating another embodiment of a pump of the invention.

Referring particularly to Figs. 1 and 2 of the drawing, the numeral 10 designates a pump housing which provides an impeller chamber 12 for an impeller 14 of rubber, or like material. The impeller 14 includes vanes 16 adapted to be flexed by a cam 18 to produce the characteristic pumping action of pumps of this nature as the impeller is rotated.

Aligned with the pump housing 10 is a housing 20 for a bearing 22, the bearing housing being shown as connected to the pump housing 10 in the particular construction illustrated and as being provided with a mounting flange 24 for mounting the pump.

The bearing 22 rotatably supports a shaft 26 having a projecting end 28 which extends into the impeller chamber 12 and is encircled by the impeller 14. Telescoped over the projecting end 28 of the shaft 26 is a deep, cup-shaped, sheet metal hub 30 of the impeller 14 which encloses the projecting end 28 of the shaft 26. The impeller 14 is bonded to the hub 30 and the latter is provided with an inwardly struck dimple or detent 32 disposed in a recess 34 in the shaft 26. This recess may either be a keyway, or a chordal recess providing a flat engageable by the detent 32. Thus, torque is transmitted from the shaft 26 to the impeller 14 by the torque-transmitting connection between the shaft and the hub 30 provided by the detent 32 in the recess 34, and by virtue of the fact that the impeller is bonded to the hub.

The pump of the invention includes sealing means 36 engaging the pump housing 10 and an axially projecting sleeve portion of the hub 30 outwardly of the impeller chamber 12 to prevent leakage from the impeller chamber, it being noted that the pump housing 10 opens to the atmosphere outwardly of the sealing means 36 so that any leakage which does occur may escape. With this construction, it will be apparent that none of the pumped fluid can come in contact with the shaft 26, being prevented from so doing by virtue of the fact that the hub 30 projects beyond the impeller 14 and is sealed relative to the pump housing 10 by the sealing means 36. Also, since the sealing means 36 engages the hub 30, and not the shaft 26, the sealing means 36 cannot produce wear of the shaft.

In order to prevent circulation of air from the surrounding atmosphere through the clearance between the hub 30 and the projecting end of the shaft 26, which clearance is necessary to provide ready installation and removal of the impeller 14 and its hub 30, I provide a sealing means 40 for producing a fluid-tight seal between the axially projecting sleeve portion of the hub 30 and the shaft. As best shown in Fig. 2 of the drawings, the sealing means 40 includes an elastomeric sealing sleeve 42 which encircles the shaft and which engages a convergent outer end 44 of the hub 30. The sealing sleeve 42 may be provided with internal annular ribs 46 to promote fluid-tight engagement with the shaft 26, and a garter spring 48 may encircle the sealing sleeve to bias it inwardly into sealing engagement with the convergent end 44 of the hub and with the shaft, but these additions or refinements are not necessary to the invention.

In the embodiment illustrated in Figs. 1 and 2 of the drawings, one end of the sleeve 42 also engages the bearing 22 to prevent leakage of air, or other fluids, into the interior of the bearing. In this connection, it should be noted that the convergent end 44 of the hub 30 tends to cause the sealing sleeve 42 to shift axially along the shaft 26 into positive sealing engagement with the bearing, due to the elastic nature of the sealing sleeve. By using a garter spring surrounding the sealing sleeve, this effect can be augmented.

An annular sealing element, such as an O-ring 50, encircles the exterior of the bearing 22 and provides a fluid-tight seal between it and the bearing housing 20, thereby preventing leakage of oil or vapor from the en-

gine to which the pump is attached, as by the flange 24.

Referring to Fig. 3 of the drawing, the embodiment illustrated therein is similar to the one just described and corresponding reference numerals are employed insofar as possible. In the embodiment of Fig. 3, the elastic sealing sleeve 42 seals only the clearance between the hub 30 and the shaft 26, and does not seal the bearing 22. Thus, in this embodiment, the sealing sleeve 42 is simply seated against a washer 52 abutting a shoulder 54 on the shaft. The function of the sealing sleeve 42 in sealing the bearing 22 in the previous embodiment, and the function of the O-ring 50 of the previous embodiment, are performed by a sealing means 56 in the embodiment of Fig. 3, this sealing means engaging the bearing housing 20 and the shaft 26 as shown.

Thus, the present invention provides a construction wherein the shaft within the impeller hub is completely isolated to reduce corrosion to a minimum, thereby insuring easy installation and removal of the impeller at all times, which is an important feature.

Although I have disclosed exemplary embodiments of my invention herein for purposes of illustration, it will be understood that various changes, modifications and substitutions may be incorporated in such embodiments without departing from the spirit of the invention as defined by the claims allowed to me and appearing hereinafter.

I claim as my invention:

1. In a pump, the combination of: a pump housing 30 providing an impeller chamber; a shaft extending into said impeller chamber; an impeller in said impeller chamber and including an impeller hub encircling said shaft, said impeller being fixed on said hub, said impeller hub loosely fitting said shaft so as to be readily removable therefrom; means for transmitting rotation of said shaft to said impeller hub; a sleeve portion fixed on said impeller hub and projecting from one end of said impeller along and encircling said shaft; and means engaging and providing a fluid-tight seal between said sleeve portion and said shaft.

2. In a pump, the combination of: a pump housing 30 providing an impeller chamber; a shaft extending into said impeller chamber; an impeller in said impeller chamber and including an impeller hub encircling said shaft, said impeller being fixed on said hub, said impeller hub loosely fitting said shaft so as to be readily removable therefrom; means for transmitting rotation of said shaft to said impeller hub; a sleeve portion fixed on said impeller hub and projecting from one end of said impeller along and encircling said shaft; means engaging and providing a fluid-tight seal between said sleeve portion and said shaft; and means engaging and providing a fluid-tight seal between said sleeve portion and said pump housing.

3. In a pump, the combination of: a pump housing 30 providing an impeller chamber; a shaft extending into said impeller chamber; an impeller hub in said impeller chamber and encircling said shaft, said impeller hub loosely fitting said shaft so as to be readily removable therefrom; a rubber impeller in said impeller chamber and bonded to said hub; means for transmitting rotation of said shaft to said impeller hub; and means engaging and providing a fluid-tight seal between said impeller hub and said shaft.

4. In a pump, the combination of: a pump housing 30 providing an impeller chamber; a shaft extending into said impeller chamber; an impeller hub in said impeller chamber and encircling said shaft, said impeller hub loosely fitting said shaft so as to be readily removable therefrom; a rubber impeller in said impeller chamber and bonded to said hub; means for transmitting rotation of said shaft to said impeller hub; means engaging and providing a fluid-tight seal between said impeller hub and said shaft; and means engaging and providing a fluid-tight seal between said impeller hub and said pump housing.

5. In a pump, the combination of: a pump housing providing an impeller chamber; a shaft having a projecting end extending inwardly into said impeller chamber; an impeller in said impeller chamber and encircling said projecting end of said shaft, said impeller including a central hub which is closed at its inner end to enclose said projecting end of said shaft and which extends outwardly along said shaft out of said impeller chamber so that the outer end of said hub is located outwardly of said impeller chamber, said impeller being fixed on said hub, said hub loosely fitting said shaft so as to be readily removable therefrom; means for transmitting rotation of said shaft to said hub; and means engaging and providing a fluid-tight seal between said hub and said shaft.

6. In a pump, the combination of: a pump housing providing an impeller chamber; a shaft having a projecting end extending inwardly into said impeller chamber; an impeller in said impeller chamber and encircling said projecting end of said shaft, said impeller including a central hub which is provided with a closed inner end to enclose said projecting end of said shaft and which extends outwardly along said shaft out of said impeller chamber so that the outer end of said hub is located outwardly of said impeller chamber, said impeller being fixed on said hub, said hub loosely fitting said shaft so as to be readily removable therefrom; means for transmitting rotation of said shaft to said hub; and sealing means engaging said outer end of said hub and said shaft for providing a fluid-tight seal between said hub and said shaft.

7. In a pump, the combination of: a pump housing providing an impeller chamber; a shaft having a projecting end extending inwardly into said impeller chamber; an impeller in said impeller chamber and encircling said projecting end of said shaft, said impeller including a central hub which is provided with a closed inner end to enclose said projecting end of said shaft and which extends outwardly along said shaft out of said impeller chamber so that the outer end of said hub is located outwardly of said impeller chamber, said impeller being fixed on said hub, said hub loosely fitting said shaft so as to be readily removable therefrom; means for transmitting rotation of said shaft to said hub; sealing means engaging said outer end of said hub and said shaft for providing a fluid-tight seal between said hub and said shaft; and sealing means engaging said pump housing and engaging said hub inwardly of said outer end thereof for providing a fluid-tight seal between said hub and said pump housing.

8. A pump as defined in claim 6 wherein said hub is a deep, one-piece, sheet metal cup, said rotation-transmitting means including an inwardly-struck detent on said cup disposed in a recess in said projecting end of said shaft.

9. In a pump, the combination of: a pump housing providing an impeller chamber; a shaft having a projecting end extending inwardly into said impeller chamber;

an impeller in said impeller chamber and encircling said projecting end of said shaft, said impeller including a central hub which is provided with a closed inner end to enclose said projecting end of said shaft and which extends outwardly along said shaft out of said impeller chamber so that the outer end of said hub is located outwardly of said impeller chamber, said impeller being fixed on said hub, said hub loosely fitting said shaft so as to be readily removable therefrom; means for transmitting rotation of said shaft to said hub; and sealing means engaging said outer end of said hub and said shaft for providing a fluid-tight seal between said hub and said shaft, including a sealing sleeve encircling said shaft and engaging said outer end of said hub, said outer end of said hub being convergent.

10. In a pump, the combination of: a pump housing providing an impeller chamber; a shaft having a projecting end extending inwardly into said impeller chamber; an impeller in said impeller chamber and encircling said projecting end of said shaft, said impeller including a central hub which is provided with a closed inner end to enclose said projecting end of said shaft and which extends outwardly along said shaft out of said impeller chamber so that the outer end of said hub is located outwardly of said impeller chamber, said impeller being fixed on said hub, said hub loosely fitting said shaft so as to be readily removable therefrom; means for transmitting rotation of said shaft to said hub; sealing means engaging said outer end of said hub and said shaft for providing a fluid-tight seal between said hub and said shaft, including a sealing sleeve encircling said shaft and engaging said outer end of said hub, said outer end of said hub being convergent; and sealing means engaging said pump housing and engaging said hub inwardly of said converging outer end thereof for providing a fluid-tight seal between said hub and said pump housing.

11. A pump as defined in claim 10 including a bearing carrying said shaft and located outwardly of said convergent outer end of said hub.

12. A pump as defined in claim 11 wherein said sealing sleeve engages said bearing to seal same.

13. A pump as defined in claim 9 including resilient means for biasing said sealing sleeve into engagement with said convergent outer end of said hub and said shaft.
